UNITED STATES PATENT OFFICE.

WEBSTER C. ESTES, OF FLATBUSH, NEW YORK.

DESIGN FOR A WOODEN BOX.

SPECIFICATION forming part of Design No. 20,669, dated April 14, 1891.

Application filed November 18, 1889. Serial No. 330,802. Term of patent 7 years.

To all whom it may concern:

Be it known that I, WEBSTER C. ESTES, a citizen of the United States, residing at Flatbush, in the county of Kings and State of New York, have invented and produced a new and original Design for a Wooden Box, of which the following is a specification.

The leading feature of this design for a wooden box is the external conoidal configuration with peripheral corrugations, the top approximating a Gothic arch in section and the sides of the bottom part being nearly vertical.

In the drawings the design of the box is represented by a section, Fig. 1, and an elevation, Fig. 2.

The configuration is conoidal, somewhat similar to the shape of the end of a rifle-bullet, the top being in section approximately a Gothic arch and the sides of the bottom portion being nearly vertical, and there are peripheral ribs or corrugations, as shown.

I claim—

The design for a wooden box, as shown and described.

Signed by me this 14th day of November, 1889.

WEBSTER C. ESTES.
